[57] CLAIM

The ornamental design for a combination handset telephone and stand, as shown and described.

DESCRIPTION

FIG. 1 is a left side and top perspective view of a combination handset telephone and stand showing my new design;

FIGS. 2 and 3 are respectively right and left elevational views thereof;

FIGS. 4 and 5 are respectively top and bottom plan views thereof;

FIG. 6 and 7 are respectively lower and upper end elevational views thereof;

FIG. 8 is a top, right side perspective view of the stand with the telephone handset removed;

FIG. 9 is a top plan view of the stand with the handset removed;

FIG. 10 is a bottom left side perspective of the stand with the handset removed;

FIG. 11 is a top left side perspective view of the handset removed from the stand;

FIG. 12 is a right side elevational view of the handset removed from the stand;

FIG. 13 is a left side elevational view thereof;

FIGS. 14 and 15 are respectively lower and upper end elevational views, with the handset removed from the stand.
